UNITED STATES PATENT OFFICE.

WILHELM BRÜGMANN, OF DORTMUND, GERMANY.

APPARATUS FOR POURING METAL INTO A SERIES OF MOLDS.

No. 929,547.

Specification of Letters Patent.

Patented July 27, 1909.

Application filed March 2, 1908. Serial No. 418,721.

To all whom it may concern:

Be it known that I, WILHELM BRÜGMANN, a subject of the King of Prussia, residing at 23 Bornstrasse, Dortmund, Germany, have 5 invented certain new and useful Improvements in Apparatus for Pouring Metal into a Series of Molds; and I do hereby declare the following to be a full, clear, and exact description of the invention.

10 In certain well known apparatus for casting iron, the liquid iron is poured in a continuous stream into a series of ingot molds which are caused to pass continuously under the stream of iron. With this method of 15 casting, the necessity for leading the stream of iron from one mold to the next is attended by drawbacks which have not been removed completely by the use of devices designed to prevent the liquid iron from flowing 20 into the space between two adjacent molds. Now according to this invention the liquid iron is poured into a series of intermittently traveling molds only while these are temporarily at rest, and when these molds 25 have resumed their travel, the stream of iron is led into a second series of molds which are caused to travel intermittently like the first series of molds, but in alternation therewith, so that when the first series of 30 molds are in motion, the molds of the second series will be at rest, and the mold of this second series which happens to be in position under the stream of liquid iron, will be filled. Then when this mold has been filled, 35 the stream of liquid iron will be led into the next mold of the first series which has been stopped and is now in position under the stream of iron ready for filling. When this mold is full, the next mold of the first 40 series is then filled, and so on.

In the accompanying drawings:—Figure 1 is a vertical central cross section; Fig. 2 a plan, and Fig. 3 a longitudinal vertical section on the line A—B of Fig. 2, illustrating one form of apparatus according to this 45 invention.

1, indicates one series of molds arranged in a circle on a turntable *c*. *m*, indicates a 50 second series of molds also arranged in a circle on a turntable *f*. The two turntables *c* and *f*, are each revolved by power, or by hand, for instance by means of a ratchet lever, at determined intervals of time through a distance equal to the width of a 55 mold. A pouring arm *b*, situated between

the two turntables is adapted to be tipped on its longitudinal axis, and it is provided at its outlet with two spouts *b*¹ and *b*², projecting on opposite sides of the channel. When the pouring arm *b* is tipped for instance toward the left (Fig. 3), the liquid iron which is run into it from a ladle *a* that has received its charge from a blast furnace, flows through the spout *b*¹, directed toward that side, with a constant fall into the mold *l* of 60 the turntable *c*, that happens to be in position underneath the stream of liquid iron issuing from the spout *b*¹. When this mold has been filled, the pouring arm *b* is tipped toward the right by means of a lever *e*, 65 worked by an operator from the platform *d*, (Fig. 2) so as to cause the stream of iron to flow through the outer spout *b*² into the mold *m* of the turntable *f*, which has been brought in the meantime into position for being filled. 70 At the same time the turntable *c* is being rotated forward through a distance equal to the width of a mold. When the mold *m* is full the pouring arm is tipped again to the left, while the turntable *f* is again ro- 75 80 tated a step forward, and so on. The pouring arm is also provided at its outlet with a longitudinally arranged overflow *g*. If any hitch should occur in the working of the apparatus, for instance, such as a stoppage in 85 the operation of the turntables, the pouring arm can be moved into its mid-position and then the stream of liquid iron can flow without danger by way of the overflow *g* into the ladle *h*, placed underneath. When the ingots have become cool they are removed 90 automatically or it may be, by hand, for instance, by the molds being tipped by means of a suitable implement so as to discharge the contained ingots on to a truck as indicated at *i*. The molds after having been cleaned by the injection of water under pressure, and then drained dry, are tipped back at *k*, into their former upright position by 95 automatic means or by hand, ready to resume their journey toward the filling point. 100

The form of the mold carriers may vary. Instead of being constructed in the form of turntables as shown, the carriers may be constituted by belt conveyers traveling in 105 horizontal or in inclined planes, or by a pair of vertical disks or wheels between which the molds are suspended so as to be capable of oscillating freely, in such a manner that the molds will always take up vertical posi- 110

tions. Or the mold carriers may be stationary, and the ladle with the pouring arm be made to move past the said carriers. In this case the pouring arm is provided with 5 movable spouts.

The pouring arm may have any suitable form. It may be composed of a receiving portion with a pouring portion distinct therefrom. The pouring portion may have the 10 form of a drum, ladle or trough.

What I claim as my invention and desire to secure by Letters Patent is:

1. A pouring apparatus for liquid metals and the like, comprising a pouring trough 15 adapted at one end to receive the molten metal from a furnace and provided with lateral discharge spouts on opposite sides of said trough and a terminal overflow spout, in combination with means for oscillating 20 said trough to pour first on one side and then on the other and series of molds arranged on opposite sides of said trough and adapted to be moved past the same to present an empty

mold to said discharge spouts first on one side and then on the other.

25

2. A pouring apparatus for liquid metals and the like, comprising a pouring trough adapted at one end to receive the molten metal from a furnace and provided with lateral discharge spouts on opposite sides of 30 said trough, in combination with means for oscillating said trough to pour first on one side and then on the other and series of molds arranged on horizontal circular carriers on opposite sides of said trough adapted to be 35 intermittently rotated to bring an empty mold beneath said pouring spouts first on one side and then on the other, substantially as described.

In testimony whereof I have signed my 40 name to this specification, in the presence of two witnesses.

WILHELM BRÜGMANN. [L. S.]
